Des. 242,358
Patented Nov. 16, 1976

242,358

TELEPHONE KEY BASE

Carl-Arne Breger, Stockholm, Sweden, assignor to Telefonaktiebolaget L M Erickson, Stockholm, Sweden

Filed Aug. 21, 1974, Ser. No. 499,266

Claims priority, application Sweden Mar. 1, 1974

Term of patent 7 years

Int. Cl. D14—03

U.S. Cl. D26—14 A

FIG. 2

FIG. 3

FIG. 4

FIG. 5

FIG. 6

FIG. 8

FIG. 1 is a perspective view of a telephone key base showing my design;

FIG. 2 is a perspective view of the side opposite to that shown in FIG. 1;

FIG. 3 is a front elevational view of FIG. 1;

FIG. 4 is a bottom plan view of FIG. 1;

FIG. 5 is a rear elevational view of FIG. 1;

FIG. 6 is a perspective view of the front and one side of a telephone key base showing a second embodiment of my design;

FIG. 7 is a perspective view the rear and side shown in FIG. 6, it being understood that the opposite side is a mirror image thereof; and

FIG. 8 is a bottom plan view of FIG. 6.

I claim:

The ornamental design for a telephone key base, as shown and described.
